UNITED STATES PATENT OFFICE.

HOWARD M. DUDLEY, OF PHILADELPHIA, PENNSYLVANIA.

DYEING-MACHINE.

1,271,144.

Specification of Letters Patent. Patented July 2, 1918.

Application filed August 3, 1917. Serial No. 134,200.

To all whom it may concern:

Be it known that I, HOWARD M. DUDLEY, a citizen of the United States, and a resident of Philadelphia, in the county of Philadelphia and State of Pennsylvania, have invented certain new and useful Improvements in Dyeing-Machines, of which the following is a specification.

My invention relates to dyeing machines 10 and refers particularly to those machines in which textile fibers are dyed under compression, the dye liquor being forced through the compressed mass.

The dyeing of fibers under these conditions 15 presents many difficulties, as it is essential that all parts of the fiber mass be treated absolutely equally by the dye liquor, as otherwise uneven results will be obtained.

This equal treatment is dependent upon a 20 number of conditions: The fiber must be uniformly and properly compressed, the liquor must be at a uniform pressure throughout the fiber mass, the formation of channels or 25 passages within the fiber mass must be avoided, the dye liquor must be of such dilution as to prevent precipitation upon the fiber, the temperature of the liquor must be properly retained and means must be employed 30 for determining the condition of the dyed fibers without interrupting the dyeing operation, opening the dyeing chamber or disturbing or sampling the fiber being dyed.

The device of my invention accomplishes 35 all of the above results in a manner economical in construction and cheap, simple, accurate and positive in operation and possesses other advantages which will be evident upon a consideration of my specification,

40 drawings and claims.

In the dyeing of fibers under these conditions, it is essential that as much as possible of the lower surface or layer of the fiber mass be subjected to the liquid, and I have 45 found that this can be accomplished to a maximum degree by allowing the fiber mass to rest upon a series of upwardly extended hollow cones, having perforated sides, particularly effective results being attained 50 when these openings are vertically extended openings of a curved character. This formation allows practically the entire lower surface of the fiber mass to be treated equally by the liquid.

A similar plate, having the hollow perforated cones downwardly extended when placed above the fiber mass, causes uniform pressure and distribution of the liquid through the compressed fiber mass.

In order to obtain a uniformly distributed 55 pressure against the faces of the foraminous plates, I introduce an approximately semi-spherical member through which the liquid is forced, said liquid supply member having within it a series of solid curved members 60 so shaped and arranged as to impinge the liquid equally and uniformly upon the faces of the plates.

In order to judge of the condition of the 65 process, I have a small dyeing device exactly 70 similar and proportionate to the larger device and so constructed that fiber inserted therein will receive exactly the same treatment as that in the larger device, the same proportionate amount of the same liquor passing 75 through both under the same pressure and temperature, so that in order to determine the condition of the dyeing, the operation in the large device need not be even interrupted, the large device need not be opened, and 80 it will not be necessary to disturb the fiber contained therein.

In the drawings, illustrating modified 85 forms of the device of my invention, similar parts are designated by similar numerals.

Figure 1 is a vertical-section of one form of my device.

Fig. 2 is a cross-section through the line 2-2 of Fig. 1.

Fig. 3 is a cross-section through the line 90 3-3 of Fig. 1.

Fig. 4 is a broken detail top plan of one of the foraminous plates.

Fig. 5 is a broken enlarged view of the 95 testing device.

Fig. 6 is a cross-section through the line 6-6 of Fig. 4.

Fig. 7 is a broken cross-section of a portion 100 of a modified form of the distributing members below the foraminous plate.

The device of my invention illustrated in the drawings, comprises a cylindrical dyeing receptacle having the side wall 10, affixed to the liquid distributing chamber 11 by means of the screw-bolts 12, 12. The distributing chamber 11 is fixed to the delivery chamber 13 of the pump 14 by means of the screw-bolts 15, 15. The receiving chamber

of the pump 14 is connected with the pipe 16, which in turn is connected with the pipe 17 having the valve 18, the pipe 17 being connected with a dissolving tank not shown. 5 The pipe 17 is also connected with the pipe 19 having the valve 20, the pipe 19 being connected with a supply of fresh water. The pipe 16 is connected with the pipe 21 having the valve 22, the pipe 21 being connected with the lower portion of a reserve tank 23. The upper portion of the dyeing receptacle is connected with an over-flow pipe 24, which enters the upper portion of the reserve tank 23. The side wall 10 of the 10 dyeing receptacle has an annular offset 25, upon which rests the foraminous plate 26. The upper portion of the side wall 10 is extended outwardly into the annular flange 27. A removable annular angular member 28 is 15 capable of insertion within the dyeing receptacle and is movable therein by means of the screw bolts 29, 29, passing through the member 28 and threaded within the member 27. The member 28 is capable of surface engagement with the upwardly extended annular members 30 of the foraminous plate 31, openings 32, 33 allowing of the passage of a liquid therethrough for purposes to be described later. A conduit 34, opening below the foraminous plate 26 is connected with the pipe 35 having the valve 36. The pipe 35 above the valve 36 is connected to the testing device 37 by means of the coupling 38, the testing device 37 having the 20 annular offset 39, in order to make a tight joint. The upper portion of the testing device 37 is similarly joined to the member 27 by means of the coupling 40, and is connected to the conduit 41, which enters the receptacle through the opening 32 into the receptacle above the foraminous plate 31. The distributing member 11 contains a series of parallel plates 42, 42, which are curved 25 to correspond with the sides of the distributing chamber 11 and which converge downwardly to an approximately sharp edge, the object of the shape of the member 11 and the plates 42, 42 being to distribute the liquid pressure uniformly and evenly. A pipe 43 having the valve 44 is connected with the 30 delivery chamber 13. A perforated steam pipe 45 is situated below the foraminous plate 26.

The foraminous plates 26 and 31 are similar in construction and comprise a series of extended hollow cones 46, 46 the sides of which have the vertical curved openings 47, 47.

The testing device 37 contains two foraminous plates 48, 48 and a dyeing chamber similar and proportionate to those of the larger device.

In the modification of the distributing chamber 11, shown in Fig. 7, the member 11 is of a concavo-convex form and the mem-

bers 42, 42, curve downwardly and inwardly to somewhat conform with the shape of the member 11.

The operation of the device is as follows:—

The annular member 28 and the foraminous plate 31 are removed, the fiber 100 is placed within the receptacle and upon the foraminous plate 26. The plate 31 and the member 28 introduced and the plate 31 forced downwardly upon the fiber 100 by means of the screw-bolts 29, 29 until the desired pressure is obtained. All of the valves are closed with the exception of valves 18 and 36 and the pump 14 started. Liquid flows from the dissolving tank (not shown) through the pipe 17, the pipe 16, the pump 14, the distributing chamber 11, the plate 26, the fiber 100, the plate 31, the opening 33, and the pipe 24 into the reserve tank 23. At 70 the same time the liquid is forced through the conduit 34, the pipe 35, the fiber within the testing device 37, the conduit 41 and the opening 32. When sufficient liquid has been 75 pumped into the device, the valve 18 is closed and valve 22 is opened and the liquid is thus given a continuous circulation through the dyeing device and the reserve tank 23. From time to time the valve 36 is closed, the testing device 37 is removed and 80 the condition of the dyeing observed and the testing device 37 replaced.

When the dyeing operation is finished, valve 22 is closed, the pump 14 stopped and valve 44 opened thus drawing the liquid 85 from the device.

The dyed goods are washed by closing valve 44, opening valve 20, starting the pump 14, and connecting pipe 24 with a drain. When the goods are sufficiently 90 washed, valve 20 is closed, the pump 14 stopped and the valve 44 opened thus draining the wash water from the device.

I do not limit myself to the particular size, shape, number or arrangement of parts 95 as illustrated and described, all of which may be varied without going beyond the scope of my invention as described and claimed.

What I claim is:—

1. In a dyeing machine, in combination, 115 a receptacle having imperforate sides, two foraminous plates within and extending across the receptacle, means for moving the plates with respect to each other, a downwardly converging and curved liquid distributing chamber below the lower foraminous plates, a series of downwardly and inwardly extended blades within the distributing chamber, and means for forcing a 120 liquid through the device.

2. In a dyeing machine, in combination, 125 a receptacle having imperforate sides, two foraminous plates within and extending across the receptacle, each plate having a 130

series of extended hollow cones with openings therein, means for moving the plates with respect to each other, a downwardly converging and curved liquid distributing 5 chamber below the lower foraminous plates, a series of downwardly and inwardly extended blades within the distributing chamber, and means for forcing a liquid through the device.

10 3. In a dyeing machine, in combination, a receptacle having imperforate sides, two foraminous plates within the receptacle, each plate comprising a series of extended hollow cones having vertical openings in 15 the sides thereof, means for spacing the plates from each other, a downwardly converging distributing chamber spaced below the lower foraminous plate, a series of parallel downwardly and inwardly curved 20 blades within the distributing chamber, a pump connected with the lower portion of the distributing chamber, an over-flow pipe above the upper foraminous plate and means for the continual circulation of a liquid 25 through the device.

4. In a dyeing machine, in combination, a receptacle having imperforate sides, two foraminous plates within and extending across the receptacle, means for moving 30 the plates with respect to each other, a downwardly converging and curved liquid distributing chamber below the lower foraminous plates, a series of downwardly and inwardly extended blades within the distributing 35 member, a smaller testing device containing foraminous plates and a dyeing chamber similar and proportionate to those of the larger device, means whereby a fiber within the testing device may be examined 40 without interrupting the passage of the liquid within the larger device, connecting means below the two lower foraminous plates for the passage of a liquid, and means for passing a liquid through the two devices.

45 5. In a dyeing machine, in combination, a receptacle having imperforate sides, two foraminous plates within and extending across the receptacle, each plate having a

series of extended hollow cones with openings therein, means for moving the plates with respect to each other, a downwardly converging and curved liquid distributing 50 chamber below the lower foraminous plates, a series of downwardly and inwardly extended blades within the distributing chamber, a smaller testing device exterior to the larger device and containing foraminous plates and a dyeing chamber similar and proportionate to those of the larger device, means whereby a fiber within the testing 55 device may be examined without interrupting the passage of the liquid within the larger device, connecting means below the two lower foraminous plates for the passage of a liquid, and means for passing a liquid 60 through the two devices.

6. In a dyeing machine, in combination, a receptacle having imperforate sides, two foraminous plates within the receptacle, each plate comprising a series of extended 70 hollow cones having vertical openings in the sides thereof, means for spacing the plates from each other, a downwardly converging distributing chamber spaced below the lower foraminous plate, a series of 75 parallel downwardly and inwardly curved blades within the distributing chamber, a pump connected with the lower portion of the distributing chamber, an over-flow pipe above the upper foraminous plate, a smaller 80 testing device exterior to the larger device and containing foraminous plates and a dyeing chamber similar and proportionate to those of the larger device, means whereby a fiber within the testing device may be examined 85 without interrupting the passage of the liquid within the larger device, connecting means below the two lower foraminous plates for the passage of a liquid, and means for passing a liquid through the two devices.

Signed at New York, in the county of New York and State of New York, this 23d day of July, 1917.

HOWARD M. DUDLEY.
